CATHODE RAY APPARATUS

Donald E. Norgaard, Scotia, N.Y., assignor to General Electric Company, a corporation of New York

Filed June 8, 1942, Ser. No. 446,231

14 Claims. (Cl. 343—11)

My invention relates to cathode ray apparatus and to circuits useful in the control thereof.

More particularly, my invention relates to cathode ray apparatus as employed in equipment for ascertaining information with respect to distant objects, and in particular for determining distance to, and the direction of, such objects.

In equipment as now employed for these purposes, radiant impulses are transmitted at regularly recurring intervals and after each impulse corresponding impulses resulting from the transmitted impulse, as by reason of reflection from remote objects, or due to operation of apparatus on such remote objects, are received over a certain time interval. The ray of a cathode ray device is deflected across its viewing screen in a predetermined path during this interval, the deflection starting just prior to transmission of each pulse. During this deflection the ray is caused to be deflected from such path by the transmitted pulse and by each returning pulse. These latter deflections are thus spaced on the viewing screen along the predetermined path in sequence corresponding to the time sequence of the reception of the different impulses affecting the cathode ray. Thus, the distance on the viewing screen of any deflection produced by a received pulse from that produced by a transmitted pulse corresponds to the distance to the remote object from which the received pulse came, whether by reason of reflection, or by reason of the operation of apparatus on said object.

One of the objects of my invention is to provide means for use in connection with such apparatus to improve the accuracy with which the distance to a remote object may be ascertained.

A further object of my invention is to provide improved means to select a particular received impulse, or echo, and to utilize such selected impulse exclusively to ascertain information with respect to the corresponding distant object. A further object of my invention is to utilize such selected impulse to determine with greater accuracy the distance to the remote object and the direction thereof.

A still further object of my invention is to provide equipment including further cathode ray oscilloscopes which are controlled exclusively by the selected impulses and which are operated in such a way as to provide indications of the direction of the distant object in one or more planes, and to provide improved indications of distance.

Still further objects of my invention relate to circuits and instrumentalities for use in the control and operation of such cathode ray apparatus to produce such indications and such objects will appear as the description of my invention proceeds.

The novel features which I believe to be characteristic of my invention are set forth with particularity in the appended claims. My invention itself, however, both as to its organization and method of operation, together

with further objects and advantages thereof may best be understood by reference to the following description taken in connection with the accompanying drawings in which Figs. 1 and 2 taken together, represent an embodiment of my invention; Fig. 3 illustrates certain characteristics of the apparatus shown in Figs. 1 and 2; Figs. 4 and 8 represent certain details of the equipment shown in Figs. 1 and 2; Figs. 5, 11a, and 11b represent certain characteristics of the apparatus shown in Fig. 4; Fig. 6 shows a modification of the equipment shown in Fig. 4; Fig. 7 illustrates certain characteristics of the apparatus of Fig. 6; Fig. 9 illustrates in detail the phase shifting apparatus represented in Fig. 2; Figs. 10a to f represent characteristics of the equipment shown in Fig. 9 and Figs. 12 and 13 represent certain additional characteristics thereof.

In Figs. 1 and 2, I have represented by rectangles, or blocks, different apparatus units the details of which it is unnecessary to consider in the present application, or the details of which are represented in other figures of the drawings. The circuit connections between these various apparatus units are represented by a single line on the diagram representing a single conductor and by the conventional representation of ground. It will be understood that one side of each circuit may be grounded and therefore the grounded conductor of each circuit is not shown on the drawing, only conductors carrying potential with respect to ground being shown on the drawing.

Referring first to Figs. 1 and 2 of the drawing, I have indicated at the left hand portion of Fig. 1 at 1, 2, 3 and 4, a plurality of directive antennae. These antennae are arranged in a single plane, in an array, and are connected through transmission lines 5, 6, 7 and 8 to a pulse transmitter 9 whereby they are supplied with periodically recurring pulses to be radiated. These pulses of radiated energy may impinge upon distance reflecting surfaces and produce echoes which are received upon the antennae 1, 2, 3 and 4. Alternatively, they may affect apparatus mounted upon a distant object, such as an aircraft, and which may be designed to operate in response to receipt of such pulses to radiate additional pulses, which are received upon the antennae 1, 2, 3, 4. Hereinafter, I shall refer to received pulses of either of these types as echoes of the transmitted pulses. Such received pulses are supplied over the transmission lines 5, 6, 7 and 8 and a common transmission line 10 to a receiver 11.

Of course, means are provided which are represented by the rectangle 10', to prevent pulses generated by the transmitter from objectionably affecting the receiver 11 because of their high intensity. Similarly, the equipment 10' includes means to reduce attenuation of received signals by the output circuit of the transmitter. One such means is described and illustrated in the herein-after referred to application Serial No. 412,452 of Richard C. Longfellow, filed September 26, 1941, now Patent 2,412,160, issued December 3, 1946. Such means form no part of my present invention and are now in common use and well known to persons skilled in the art. It may comprise a simple diode, not shown, connected across the line 10 extending to the receiver at a suitable point and biased to be normally nonconductive and to be rendered conductive by the intense pulses produced by the transmitter. The line 98 extending from the junction point with line 10 to the transmitter should be one having high impedance when the transmitter is inactive so as not to attenuate received echo pulses.

The time of reception of any pulse after radiation of the previously transmitted pulse is dependent upon the distance to the remote object and is utilized as a measure

of that distance. Accordingly, these pulses are caused to affect a cathode ray oscilloscope 12 to produce an indication thereon such as that indicated at 13, from which such distance may be determined.

The circle 13, which I have indicated in Fig. 2 may represent the screen of the cathode ray oscilloscope 12. During a predetermined time including the time of emission of any transmitted pulse, the cathode ray, or beam, of the cathode ray oscilloscope is caused to deflect horizontally across this screen in a straight line as indicated at 14. It is also caused to be deflected vertically from this straight line by each of the pulses affecting the receiver including the transmitted pulse. The deflection produced by the transmitted pulse may be that indicated at 15 for example, and that produced by echoes may be those represented at 16 and 17. The distance between the deflections 15 and 16 and 15 and 17 is a criterion of the distance to the remote objects from which the corresponding pulses were received.

The time required for the cathode ray to be deflected across the screen indicated at 13 may be a time comparable to the time required for a transmitted pulse to travel to a remote object 100 miles away, for example, and return to the receiving antenna. Thus, echoes from any objects along the effective beam of the antenna and within the distance of 100 miles may appear upon the screen.

It may be desirable, however, to space the indications upon the screen of such echoes more widely thereon, and accordingly, means are provided in the equipment, including switches 20 and 21, whereby the beam is deflected across the screen in the time required for the pulse to travel 25 miles and return. The indication produced may then be that represented at 13'. Here the transmitted pulse is represented by the somewhat wider deflection 15' and the remote object, which previously produced the deflection 16, is indicated by deflection 16', whereas no deflection corresponding to deflection 17 appears upon the screen since deflection 17 is produced by an object more than 25 miles away.

The representations within the circles 13 and 13' are somewhat exaggerated but serve adequately to indicate the principle of operation of the apparatus.

The control switches 20 and 21 are connected together mechanically for unicontrol and have two positions corresponding to these different ranges of the equipment. When they are in the left hand position, the indication represented within the circle 13 is produced corresponding to a range of 100 miles, whereas when in the right hand position, the indication represented at 13' is produced corresponding to a range of 25 miles. The circuits including these switches will be more particularly discussed in connection with Fig. 8 of the drawing.

It is highly desirable in such equipment to provide a more accurate indication of the distance to an object producing an echo which may be observed upon the screen of the cathode ray oscilloscope 12 than that obtainable from the screen itself. To this end a second cathode ray oscilloscope 23 is provided. The cathode ray of this oscilloscope is normally extinguished, or cut off, as by reason of voltage applied to the control electrode 24 thereof and is caused to appear and to be deflected across the entire width of the screen thereof as indicated at 25 during a very short portion of the time during which the ray of oscilloscope 12 is deflected across its screen. This deflection may be caused to occur in approximately the interval of a single received pulse, or echo, for example, which the operator may wish particularly to observe.

That is, the operator may observe upon his indicator 12 a particular deflection which he may consider to be produced by a particular remote object the movements of which he wishes carefully to observe. He therefore makes proper adjustments to cause the range indicator

23 to produce its entire sweep during the short aperture of time in which the echoes from that particular object are received. The received echo is then applied to the control grid of the range indicator 23 to increase the intensity thereof in response to the echo. Thus, a bright spot appears in the line produced by the cathode ray on the screen of the range indicator at a point thereof corresponding to receipt of the echo.

Further means are also provided to produce upon the screen of the oscilloscope a vertical deflection of predetermined form, as, for example, the inverted V shown at 35 on the drawing, and which is movable in a manner later to be explained, to accurate coincidence with the bright spot produced by the received echo. The adjustment of this means required to produce the coincidence of the inverted V and the bright spot produced by the echo then constitutes the required more accurate criterion of distance to the object producing the echo. The means for effecting this adjustment, and the operation thereof, will be fully explained in connection with Figs. 2 and 9.

In the left hand portion of Fig. 2 two additional cathode ray oscilloscopes 50 and 51 are shown, the first of which bears the legend "Elevation" and the second of which bears the legend "Train." These cathode ray oscilloscopes respond likewise only to echoes which occur during the same aperture of time during which the range indicator responds. They thus respond only to the echoes which are shown on the "Range" indicator. They are utilized to indicate the direction of the object producing this echo which is received during this aperture of time. These cathode ray oscilloscopes are controlled by mechanism 52 by which the directional properties of the antennae array 1, 2, 3, and 4 are changed in different, planes, and by which the axis of directivity of the array is shifted cyclically through four positions, two in the vertical plane, or "in elevation," and two in the horizontal plane, or "in train." The received impulses, when the directive axis is in the vertical plane, are supplied to vertical deflection plates of the Elevation indicator 50 and produce two deflections 54 and 55 thereon, each in position corresponding respectively to one position of the directive axis in the vertical plane. That is the deflection 54 is produced by the echo when the directive axis is in one position in the vertical plane and the deflection 55 is produced by the echo when the directive axis is in the other position in the vertical plane. The height, or extent, of these deflections is dependent upon the intensity of the received echo pulses which produces them. Thus, the relation between the heights of these deflections constitutes an indication of the direction to the remote object in the vertical plane.

The "Train" indicator operates in exactly the same way but with respect to the horizontal plane, and thus produces an indication of the direction of the remote object in the horizontal plane.

As previously stated, the Elevation, Train and Range indicators all operate to produce their respective indications in response to echoes received during the same brief aperture of time, this aperture of time being but a minute fraction of the time during which the control operator's indicator responds to echoes. It is desirable, therefore, that this aperture of time be indicated upon the viewing screen of the control operator's indicator. This is brought about by controlling all of these indicators by a single square wave pulse, indicated at E in Figs. 1, 2 and 3, and which is properly synchronized in variable time relation with the radiated pulses. This pulse E I shall refer to as the "aperture" pulse. This pulse is supplied, through channels later to be described, to the control electrodes of each of the elevation, train, and range indicators to turn the beam on during the aperture pulse, this beam being extinguished at all other times. It is also supplied to the vertical deflection plates of the control operator's indicator and produces the square shouldered deflections 36 and 36' as shown in Fig. 2 and at the top of which

the deflections 16 and 16' respectively appear, either of the latter two being produced by the echo to be selected.

Thus the operator, observing the deflection 16, or 16', effects suitable adjustment of the equipment to move the square shouldered deflection 36 or 36', along the screen until the echo deflection 16, or 16', as the case may be, is superposed on it. The other indicators then respond only to this selected echo.

Having now generally indicated the character of the equipment to be described, I shall proceed with a more detailed description of its structure and operation.

In the lower portion of Fig. 2 of the drawing, I have represented at 56, by the legend "Oscillator," a source of oscillations which may have a frequency of approximately 82 kilocycles, for example. This may be any suitable source of oscillations of constant frequency, and preferably is an oscillator of the crystal-controlled type. This oscillator generates oscillations which control the entire equipment.

These oscillations are supplied through a frequency divider 60, which produces square wave pulses indicated on Fig. 2 by the curve A. These pulses are also shown by the curve A of Fig. 3. They have a frequency of 656 cycles for example, and each pulse has a duration of 300 microseconds, corresponding approximately to the time required for a radiated pulse to travel to a remote object 25 miles away and return. The interval of this wave A between pulses is of about four times this length, or corresponds to approximately 100 miles. Of course any other ratio between the two intervals of this wave may be chosen, depending on the ratio between the two distance indications it is desired to produce on the screen of device 12.

This wave A is supplied to a transmitter synchronizing generator 61, which generates further pulses represented at B in Figs. 1 and 3 and which are supplied over conductor 62 to the transmitter 9 where they synchronize the radiated pulses. These pulses B, as indicated by the relation between the curves A and B of Fig. 3 are of much shorter duration than the pulses A and occur just at the end of the pulses A.

In Fig. 3 the curves A to M are drawn to represent voltage variations plotted with respect to the same time base. This is true also with respect to the curves N to T of Fig. 3 but the curves N to T are plotted with respect to a different time base than are curves A to M. These time bases will appear as this description proceeds.

The pulses A are supplied to further equipment 63 which is designated on the drawing as the control operator's 100 miles blanking and sweep generator, since it generates pulses which control the horizontal sweep and the cut off periods of the cathode ray of the control operator's indicator 12. These latter pulses appear upon conductor 64 and are represented by the curve C in Figs. 2 and 3. These pulses C are of the same frequency as the pulses A and occur simultaneously therewith but are slightly shorter than the pulse A for reasons which will later be explained.

These pulses C are supplied to the left hand contact of the control operator's range selector switch 20 and thence through this switch when in its left hand position, equipment 65, conductor 66, and resistance 67 to capacity 68. The wave C, is integrated by the network 67, 68, i.e. potential builds up gradually across the condenser 68 during the positive pulse and this condenser again discharges during the interval between these pulses. Thus, a saw-tooth wave is generated upon the condenser 68, as represented by the curve I of Fig. 3. This saw-tooth wave on condenser 68 is amplified by amplifier 69 and is supplied between the horizontal deflection plates of the control operator's indicator 12. It thus causes the horizontal deflection of the cathode ray.

The wave C is also supplied through amplifier 70 to the control electrode 71 of the cathode ray device 12 with such polarity as to extinguish the cathode ray during the

short positive pulse of the wave C. Thus, the cathode ray is on during the long portion 72 of the saw-tooth wave I, while it is being deflected across the screen, and off during the short portion, or retrace period, 73 thereof 5 while the wave is returning to the starting point of its forward deflection. This long portion of the wave I, as previously indicated, is of a duration corresponding to the 100 mile range of the equipment, and begins slightly ahead of the corresponding transmitter synchronizing pulse of the wave B indicated in Fig. 3.

The signal which is received from the receiver 11 is supplied through a mixer 75, amplifier 76, conductor 77, and amplifier 78 to the vertical deflection plates of the cathode ray oscilloscope and thus produces the vertical deflections of the beam corresponding to the radiated and received impulses. The signal which appears at the output of the receiver 11 may have the form represented by the curve G of Figs. 1 and 3 in which the transmitted pulse is indicated at 15" and certain echoes thereof at 16" and 17", these pulses, of course, producing the deflections 15, 16 and 17 indicated in the circle 13 of the control operator's indicator.

The control operator's 100 mile blanking and sweep generator 63 also supplies a pulse -C of the same form 25 and frequency as the pulse C but of opposite polarity over conductor 85 to the 25 mile blanking and sweep generator 86 which in turn produces pulses, as indicated at D in Fig. 3, which it supplies to a low frequency phase shifter 40. This low frequency phase shifter 40, operates 30 in a manner which will be more particularly described in connection with Fig. 9 to synchronize an Aperture Generator 30. This generator produces the aperture pulses, designated E in Figs. 1, 2, and 3, and which I refer to 35 herein by that name because they determine the brief aperture of time during which the Elevation, Train and Range indicators respond. They are variable in their time of occurrence, by variation of phase shifter 40, and may occur at any time within the duration of the negative pulse D, as indicated by the dotted lines on curve 40 E of Fig. 3.

These aperture pulses E are supplied over conductor 80 to mixer 75 where they are mixed with the received signal. They are represented at 36" of the curve H of Figs. 1 and 3. They are thus supplied to the vertical deflection 45 plates of the control operator's indicator and produce the square shouldered deflection 36 or 36', indicated in the circles 13 and 13' respectively of Fig. 2. This deflection indicates the interval, or aperture, of time during 50 which the other indicators 23, 50 and 51 respond and it is movable along the length of the horizontal distance 14' by variation of the low frequency phase shifter 40. It may thus be adjusted to embrace any time interval within that of the negative pulse D during which a desired echo, such as that indicated at 16', is received.

Since the echo 16 is received simultaneously with occurrence of the aperture pulse, it appears as a further deflection at the top of the deflection produced by the aperture pulse, the corresponding electromotive forces having been combined aidingly in the mixer 75.

Let us assume that the operator, having his range selector switch 20 in the left hand position, observes a deflection such as that indicated at 16 upon the cathode ray oscilloscope screen at a position indicating that the remote object producing this deflection is within 25 miles of the equipment and that he desires to observe this deflection with greater particularity. He, therefore, first throws the switch 20 to its right hand position. Impulses of the same character as the impulses C but of opposite polarity are supplied from the control operator's 65 100 mile blanking and sweep generator 63 over conductor 85 to the control operator's 25 mile blanking and sweep generator 86. This device supplies pulses of the form indicated at D to the right hand terminal 87 of 70 the control operator's range selector switch. These pulses 75

D have the time relation to the pulses C, which is indicated by the curves C and D of Fig. 3. It will be seen that the pulses D are of the same frequency and duration as the pulses C but that the pulses D occur just at the end of the pulses C and are of opposite polarity. These pulses are supplied through the switch 20 in its right hand position, apparatus 65, and conductor 66 to the network 67 and 68 and result in a saw-tooth wave upon the condenser C of the form indicated at J in Fig. 3. This saw-tooth wave is amplified by the horizontal deflection amplifier 69 and supplied to the horizontal deflection plates of the cathode ray oscilloscope 12. The wave D is also supplied through the amplifier 70 to the control electrode of the cathode ray oscilloscope with such polarity that the beam in the cathode ray oscilloscope is interrupted during the entire period of the long portion 72' of the saw-tooth wave and is present during the short portion 73' of the saw-tooth wave J, this short portion 73' having a duration corresponding to the 25 mile interval. Thus the ray is deflected across the screen during this short portion of the wave J and is blanked out during the long, or retrace portion hereof.

The signal and aperture pulses are supplied to the vertical deflection plates as before with the result that the indication is that indicated in the circle 13' in which the deflection 16', corresponding to the deflection 16, occurs more widely spaced from the deflection 15' than does the deflection 16 from the deflection 15. In other words, the indication now produced upon the cathode ray oscilloscope screen is a magnified version of the first quarter of that which was previously produced with the switch 20 in the left hand position.

The waves I and J are waves having equal variations about an alternating current axis. They may be amplified by amplifier 69 which may be of the balanced or push pull type and so biased that these variations extend symmetrically about the bias over the whole range of the anode current grid voltage characteristic for true reproduction on the output current thereof.

The operator now desires to determine with greater accuracy the distance to the object producing the deflection 16' and the direction of that object. He therefore adjusts his phase shifter 40 to such a position that the square shouldered deflection 36 embraces the deflection 16' to be examined, i.e. to such a position that the deflection 16' is superposed on the square shouldered deflection. The aperture pulses E, which are supplied from conductor 80 to mixer 75 to produce the square shouldered deflection 36', as previously indicated, are also supplied to a saw-tooth wave generator 120, which they synchronize, and which produce a saw-tooth wave on each of conductors 121, 122, and 123. This saw-tooth wave is indicated by the curve L of Fig. 3. The short portion of this saw-tooth wave L has the same duration as the aperture pulse. The saw-tooth wave on conductor 122 is supplied through amplifier 124 to the horizontal deflection plates of the "Range" indicator 23 and produces the horizontal deflection of the beam thereof across the screen. Similarly the saw-tooth wave on conductors 121 and 123 are supplied through horizontal amplifiers 116 and 118 respectively to the horizontal deflection plates of the Elevation and Train indicators 50 and 51 and produce the horizontal deflection of the beam thereof across the full width of the viewing screens of those indicators. Thus the cathode rays of each of the indicators 50, 51, and 23 produce simultaneous, synchronous, horizontal deflection across the whole width of their respective viewing screens during the time of the square shouldered deflection 36' on the control operator's indicator 12.

The aperture pulse on conductor 80 is also supplied to a mixer and clipper 31 to which signal from receiver 11 is supplied. This mixer and clipper includes any suitable, preferably electron discharge, circuit capable of transmitting the received signal to its output only when

the aperture pulse is applied to it. Thus, the aperture pulse is reproduced in its output circuit and is modulated by the received signal, as indicated at K in Figs. 1 and 3. In these curves K the square pulse represents the aperture pulse and the projections k thereon represent the desired selected echo, all other echos having been excluded from this output circuit.

The wave K is applied through amplifier 34 to the control electrode 24 of the Range indicator and operates to turn the ray on during the short portion of the saw-tooth wave on conductor 122. It is off at all other times. Thus a horizontal visible line is produced on the viewing screen of the Range indicator. The intensity of the beam, however, is varied in accordance with the received signal and is thus more intense during the echo indicated at k. This produces one or more bright spots on the screen of the Range indicator at positions corresponding to the time in the aperture pulse when the selected echoes are received.

Thus the adjustment of the low frequency phase shifter determines the time of occurrence of the aperture pulse and hence the position of the bright spots on the range indicator and it thus constitutes means whereby the distance to the remote object producing one of the bright spots may be determined. It so happens, however, due to manufacturing variations and inaccuracies in the low frequency phase shifter, that the time of occurrence of the aperture pulse does not agree, with desired accuracy, with the calibration which may be provided upon the dial, which may be associated with its control member. Such a calibrated dial is indicated at 88 in Fig. 2 as co-operating with an index on the control member 89. Accordingly, means are provided whereby the adjustment of this member 89 to a point on the dial 88 agreeing more accurately with the time of occurrence of the received echo, may be made.

This means comprises means for supplying pulses of much higher frequency than the aperture pulses to the Range indicator, a large number of such pulses occurring 40 for every aperture pulse and one occurring during each aperture pulse. These pulses are supplied to the vertical deflection plates 45 of the range indicator and produce the inverted V-shaped deflection indicated at 35 in the circle 25. The time of occurrence of these pulses, which I refer to as target marker pulses, is varied synchronously with the variation of the aperture pulses but by reason of their high frequency their time of occurrence may be more precisely controlled. Thus the operator adjusts his control member 89, which varies the time of occurrence of both the aperture pulse and the target marker pulse until the inverted V-shaped deflection 35 coincides with the bright spot produced by the echo. The distance may then be accurately read from the scale 38.

These target marker pulses are indicated at F in Figs. 2 and 3. The wave F of Fig. 3 for simplicity, indicates only that one of the target marker pulses which occurs during the aperture pulse E. The synchronous movement of the pulses F and E with respect to time is indicated by the same pulses represented by dotted lines at e and f.

These target marker pulses F are produced from the sine wave of the 82 kilocycle oscillator 56, which sine wave is supplied to the target marker generator 42 through a high frequency phase shifter 44. One of these pulses F occurs for each cycle of the 82 kilocycle sine wave, or 125 for each aperture pulse. Each pulse of wave F is much shorter than a pulse of wave E and one pulse F occurs during a pulse E and 124 pulses of wave F occur between each two successive pulses of wave E.

The two phase shifters 40 and 44 are geared together for variation by a variable control member 89 and in proper ratio to cause the same shift of the pulses F as of pulses E so that upon relatively small movement of 75 phase adjustment member 89 the aperture deflection 36'

on indicator 12, and the time over which the range indicator operates shifts but slightly, and imperceptably, as seen on indicator 12, still, the bright spot on indicator 25 may move considerably with respect to inverted V-shaped deflection as seen on the screen of the range indicator. This indicator thus produces a vernier indication for the adjustment of the member 89 to a position corresponding to the distance to the object producing the echo. When the vertex of the inverted V equally divides the bright spot on the range indicator, the distance to the remote object may be read from the scale 88 which is arranged to cooperate with the member 89.

The control member 89 may be suitably connected or geared to a position transmission device 97, which may comprise a selsyn device whereby the position of indicator 89 on scale 88 may be reproduced at a remote point, as for remote control and indication purposes.

The detail structure and operation of the phase shifters 40 and 44 will later be explained in connection with Figs. 9 to 12 of the drawing.

The operator having determined the distance to the remote object producing the deflection under examination may now desire to determine the direction of this object. Of course, a rough indication of the direction is obtained from the approximate position of the antenna array, since it has a marked directional characteristic. The directional properties of the antenna do not permit sufficiently accurate data to be obtained without the use of specially designed train and elevation indicators working together with certain special characteristics of the antenna. The operator, therefore, refers to his elevation and train indicators which are responding to the same echo and are operating only during the time of the same aperture pulse.

To understand the operation of the elevation and train indicators it is desirable first to consider the system whereby variation of the axis of directivity of the antenna system is obtained. This system comprises the antennae 1, 2, 3, and 4, the transmission lines 5, 6, 7 and 8, and the switch mechanism 52 previously mentioned. This equipment is fully described and claimed in copending applications of Lawrence M. Leeds, Serial No. 410,836, filed September 15, 1941, entitled Directional Radio System, now U.S. Patent No. 2,412,159, and of Richard C. Longfellow, Serial No. 412,452, filed September 26, 1941 entitled Directive Radio Systems now U.S. Patent No. 2,412,160, and both of which applications are assigned to the same assignee as my present application.

Each of the antennae 1, 2, 3, and 4 may comprise four radiating half-wave sections *a*, *b*, *c*, and *d*, the sections *a* and *b* being end to end and the sections *c* and *d* being end to end and the sections *a* and *b* being spaced a half wave length from the sections *c* and *d*. The antennae 1 and 2 are spaced end to end and similarly the antennae 3 and 4 are spaced end to end, the antennae 1 and 2 being spaced a half wave length from the antennae 3 and 4 and all of the antennae being spaced in the same plane. The spacing of these elements in the drawing is chosen for clarity and simplicity of illustration.

Antennae 1 and 4 are connected together by means of a transmission line 90 through impedance matching devices 91 and 92 whereby the impedance of the unbalanced transmission line 90 is matched with the balanced impedance of the respective antennae. The antennae 2 and 3 are likewise connected together through transmission line 93 and impedance matching devices 94 and 95, the latter being utilized for the same purpose. Points on these lines 90 and 93, equally spaced from the antennae 1, 2, 3, and 4 respectively are connected through the transmission lines 6, 8, 7 and 5 to a common point 96 and thence through a transmission line 98 to the transmitter 9. A suitable point on the transmission line 98 is also connected through the transmission line 10 to the receiver 11. Of course, means are included, which is represented by rectangles 10' to protect the receiver

from the intense pulses produced by the transmitter and to prevent attenuation of received pulses by the transmitter 9.

As thus arranged, the axis of directivity of the array is varied in position in accordance with the transmission lines over which energy is transmitted between the array and the transmitter or receiver. Mechanism 52 operates to confine the transmission of energy to particular lines thereby to control the axis of directivity of the array.

10 The mechanism 52 comprises a rotatable condenser having a rotor of the shape of half of a disk, and which cooperates with a plurality of stator plates 100, 101, 102 and 103, the rotor being grounded as indicated at 104. Each of these stator plates is connected through a respective transmission line 105, 106, 107 and 108 to a point on the corresponding transmission lines 6, 5, 7, and 8. These transmission lines 105 to 108 may each have a length equal to a quarter of the wave length at the frequency at which the system operates, or an odd multiple thereof.

15 20 With the rotor electrode in the position shown, low impedance is produced between ground and each of the stator electrodes 100 and 101, whereas high impedance exists between ground and the stator electrodes 102 and 103. Due to the impedance inversion effect of the transmission lines 105, 106, 107 and 108, by reason of the lengths thereof, a high impedance is produced on transmission lines 5 and 6 at the points 105' and 106' to which these lines are connected and similarly low impedance is produced on transmission lines 7 and 8 at the points 107' and 108' to which the transmission lines 107 and 108 are connected.

25 30 Thus lines 7 and 8 are disabled, being effectively short circuited at the points 107' and 108', whereas lines 5 and 6 are effective. Points 107' and 108' are so spaced from the point 96 and also from transmission lines 90 and 93 that the short circuit at the point 107' and 108' is ineffective to disable these other lines 5, 6, 90 and 93. Thus energy is transmitted between the transmitter 9 and the array and between the array and the receiver 11 over the lines 5, 6, 90 and 93. However, since the path over lines 90 and 93 to the antennae 2 and 4 is longer than that to the antennae 1 and 3 the wave exciting antennae 2 and 4 is delayed in phase with respect to the wave exciting antennae 1 and 3. This means that the beam propagated by the antennae array is propagated at an angle in the horizontal plane to the left of the normal of the array. Similarly the response of the array is greatest to waves received from that direction.

35 40 45 If the rotor of the device 52 now be rotated counterclockwise through 90° then transmission takes place over lines 6 and 8 with the result that the wave which excites antennae 3 and 4 is delayed with respect to that which excites antennae 1 and 2 and the axis of directivity of the system lies in the vertical plane at an angle above the normal of the array. If the rotor 52 be rotated through 180°, then transmission occurs over lines 7 and 8 and antennae 1 and 3 are energized in delayed phase relation with respect to antennae 2 and 4 and the axis of directivity lies in the horizontal plane at the right of the normal of the array.

50 55 60 If the rotor be rotated through 270° the axis of directivity lies in the vertical plane at an angle below the normal of the array. Thus as the rotor 52 rotates the axis of directivity of the system both with respect to transmission and reception rotates about the surface of a cone through the four positions in cyclical sequence.

65 70 75 The rotor 52 is driven by means of a motor 110 on the shaft to which is mounted a generator 111, which produces a pulse such as that indicated in Figs. 1 and 3 at 112 on the curves N. At one point in each rotation of the condenser, these pulses 112 occur, their occurrence being at a 60 cycle rate. These pulses are supplied to the square wave generator 113 which produces a square wave of the form shown at O in both Figs. 1 and 3. This square wave O is supplied over conductor 115 to the horizontal deflection amplifier 116 of the elevation indi-

cator. It is also supplied over conductor 117 to the horizontal deflection amplifier 118 of the train indicator. In both cases it serves to control the steady potential about which the saw tooth outputs from these amplifiers oscillate. These amplifiers, it will be remembered, amplify the saw-tooth wave produced by the horizontal deflection generator 120, which is controlled by the aperture pulse wave, and they operate to deflect the ray of the elevation and train indicators across the screen during the aperture pulse.

These saw-tooth oscillations are reproduced at the output of the horizontal amplifiers 116 and 118 where they appear in the form indicated by the curve T on Figs. 2 and 3, the oscillation being about one axis *a* during one portion of the wave O and about a different axis *b* during the second portion of the wave O. This is accomplished by mixing the two waves L and O in the amplifiers 116 and 118. This means that the horizontal deflection of the beam of the cathode ray oscilloscope occurs about one center during the one portion of the wave O and about a different center during a second portion of the wave O. Since the saw-tooth wave produced by generator 120 is of higher frequency than the sixty cycle square wave, the beam is deflected across the scale a number of times about each center before any change to the other center.

The square wave O produced by generator 113 is also supplied to a frequency doubler 140 having two output circuits 141 and 142. The frequency doubler 140 produces a square wave of the form indicated at P in Figs. 1 and 3 on the circuit 141, and a square wave of the form indicated at Q of Figs. 1 and 3 on the circuit 142. These waves are identical but the wave Q is displaced in phase by 180° with respect to the wave P. These waves P and Q are supplied to respective mixers 143 and 144 to which the aperture pulse from conductor 80 is also supplied. These mixers 143 and 144 are so arranged that no output is produced except during an aperture pulse and then only those aperture pulses which occur during the positive portion of the respective wave P or Q. That is, the aperture pulse is reproduced at the output of these mixers only during the positive portions of the waves P and Q. The result is that the aperture pulses appear in groups at the output of mixer 143 and 144, as indicated by the curves R and S in Figs. 1 and 3, which curves pertain, respectively, to the conductors 145 and 147, the groups of aperture pulses of the curve S being displaced in phase by 180° from the similar groups of the curve R. The pulses represented by the curve R are supplied over circuit 145 and amplifier 148 to the control electrode of the train indicator, whereby they turn the beam of the train indicator on during the period of the different aperture pulses. The aperture pulses of the wave S are supplied over circuit 147 and amplifier 146 to the control electrode of the elevation indicator where they turn the beam of this indicator on during the occurrence of the aperture pulses.

Now it will be observed from the time relationship between the curves R and O of Fig. 3 that the beam of the train indicator is on only during the periods of the aperture pulses which occur during the intervals T_1 and T_2 of the wave O. These are periods during which the directive axis of the array is respectively to the right and to the left of the normal of the array in the vertical plane. The received signal during these times, but only during these aperture pulses, is supplied from the receiver 11 through the mixer and clipper 31, apparatus 150, circuit 151, vertical amplifier 132 to the vertical deflection plates of the train indicator. Thus, when the directive axis of the array is to the right of normal in the vertical plane, the beam of the train indicator is turned on during the period of the aperture pulses of the curve R, it is swept across the screen during the more steep portion of the saw-tooth wave of the curve T, which occurs during the aperture pulse and which is supplied over the circuit 123; and it is deflected vertically by the signal from the mixer

and clipper 31, which is supplied over circuit 151. It therefore produces the deflection such as that indicated at 136 in Fig. 2 in accordance with the strength of the received signal.

When the directive axis of the array is to the left of the normal, as during the time T_2 , the same operation occurs but the horizontal deflection of the beam is about a different center, or the deflection starts from a different starting point, as indicated by the curves O and T, and the result is, that the vertical deflection on the screen produced by an echo from the same remote object appears, as indicated at 135, at a different position on the screen.

Since the directive axis is now different, the intensity of the received signal may be different, and may be smaller, with the result that the deflection 135 may be smaller as indicated, than the deflection 136, depending upon the direction to the remote object.

If the antenna array be rotated about a vertical axis until the heights of the two echo signals 135 and 136 on indicator 51 are equal, then a plane normal to that of the antenna and passing through this axis also passes through the object from which the reflections are received. A sel-syn position transmission system may then be employed, in a manner not shown, to transmit the position of the antenna about the horizontal axis to a central point, as was previously described with respect to range information.

The operation of the elevation indicator is exactly the same as that of the train indicator but it occurs during the times E_1 and E_2 of the wave O when the directive axis is in the vertical plane at positions respectively above and below the normal of the array. The signal is supplied to this device from the mixer and clipper 31 through apparatus 130, conductor 131 and amplifier 152 to the vertical deflection plates of the indicator.

If the antenna be rotated about a horizontal axis until the heights of the two echo pulses 54 and 55 on indicator 50 are equal, then a plane normal to that of the antenna array and passing through this axis also passes through the object from which the reflections are received. This locates the object in elevation and the position of the antenna about a vertical axis may be transmitted by suitable mechanism not shown, to a desired remote point.

It will thus be seen that the elevation, train and range indicators all respond only during the short aperture of time which is indicated by the deflection 36 or 36' upon the control operator's indicator. The range indicator responds during all aperture pulses, whereas, the train and elevation indicators respond during alternate intervals as determined by the groups of aperture pulses of curves R and S. The operator, by means of his mechanical device 89 and the two phase shifters, may shift this aperture of time to such a point as to bring about the operation of the elevation, train and range indicators during reception of a particular echo, which he may observe on the control operator's indicator, and which he adjusts the equipment to select. He may thus determine with the aid of the range indicator and device 89 the accurate distance to the object producing the echo, and from the elevation and train indicators the direction of the object producing the echo.

As previously stated, the aperture pulse is supplied through the mixer and clipper 31 and buffer amplifier 32 and amplifier 34 to the grid 24 of the range indicator, and it is also supplied from the mixer and clipper through apparatus 130 and 150, respectively, to the vertical deflection electrodes of the elevation and train indicators. The form of the wave produced upon the conductors 33, 151 and 131 at the output respectively of the buffer amplifier 32, apparatus 150 and apparatus 130 is indicated respectively by the curves K and M of Fig. 3, the curve K applying to the circuit 33 and the curve M applying to the circuits 151 and 131.

The apparatus 31, 130 and 150 by which these curves

are produced is indicated in detail in Fig. 4 and comprises electron discharge devices 160, 161 and 162. The discharge device 161 is supplied with anode current through a resistance 163. The discharge device 160 is supplied with anode current through the lower portion of this resistance 163 and through additional resistances 164 and 165. The signal from receiver 11 is supplied through coupling condenser 166 to the control electrode of the discharge device 160. The aperture pulse, after being reversed in polarity by the polarity reverser 81 of Fig. 1, which may be a single stage amplifier, is supplied over conductor 82 to the control electrode of the device 161. The anode of the device 161 is coupled through a condenser 170 to the screen electrode 171 of device 160. Positive potential is supplied to this screen electrode 171 through a resistance 172 from a tap on the bleeder resistance 173.

Normally the discharge device 160 is biased beyond cut-off to such an extent that no anode current flows therein, and the signal applied through condenser 166 is not normally reproduced in the anode circuit. The discharge device 161, however, normally passes a large anode current. The aperture pulses are supplied in negative sense to the control grid 181 of the discharge device 161 and therefore produce a reduction of current in resistance 163 during the period of the aperture pulses. The potential on the anode of this device 161 therefore rises. This rise in potential produces a rise in potential on screen grid 171 of the device 160 by reason of condenser 170. This rise in potential on screen grid 171 during the periods of the aperture pulses produces a flow of current in the anode of device 160 during these pulses, and of course, at this time this current is modulated by the received signal applied through condenser 166 to the control grid of the device 160. Therefore, a potential wave, such as that indicated at K, is produced on conductor 180, this wave comprising the aperture pulses in a negative sense, the crest of each pulse being modulated by the received signal as indicated at k.

This wave K may be supplied over conductor 180 to the buffer amplifier 32 of Fig. 1, amplified thereby, and supplied through the further amplifier 34 of Fig. 2 to the control electrode of the Range indicator, thereby to produce the bright spot on the viewing screen at the position corresponding to the received echo.

The amplifier 162 of Fig. 4 produces the wave M of Figs. 1 and 3. It has its cathode connected through a bias resistor 182 to ground and thence through grid resistor 183 to the control electrode thereof. This control electrode is connected through condenser 184 and resistance 164 to a variable tap 185 on resistance 163. The position of the tap 185 and the value of resistors 164 and 165 are so chosen that the grid of device 162 is driven in the positive direction during the aperture pulse so that the anode potential on the device 162 drops during the period of the aperture pulse. Thus the voltage on this anode is as indicated by the curve M in Figs. 1, 3 and 4.

It will be observed that the variation in current in resistance 163 produced by device 161 during the aperture pulse tends to drive the point 186, to which the control electrode of device 162 is coupled, more positive, while the variation in current in resistance 165 and 164 and the lower portion of 163 produced by the aperture pulse upon discharge device 160 tends to drive the point 186 less positive. Thus the position of the tap 185 upon resistance 163 and the values of resistances 164 and 165 may be so chosen that the point 186 is varied in potential in either direction as desired, during the aperture pulse. For reasons presently to be explained, I prefer that they be so chosen that the point 186 is driven positively by the aperture pulse. Since this pulse is applied to the grid of device 162 the anode thereof is driven negatively, as indicated by the curve M.

The signal affects only the discharge device 160, pro-

ducing an increase in current in the device 160 thereby lowering the potential at the point 186 in accordance with the signal during the aperture pulse. The potential on the anode of device 162 during the aperture pulse then varies as indicated at k' in Figs. 3 and 4.

This potential is supplied over the long conductor 151 which may be the center conductor of a concentric transmission line to the line-terminating resistance 190 which may be located near indicator 51. This resistance 10 may be shunted by a potentiometer 191 the variable tap 15 of which is connected to the grid of a discharge device 192. The anode of this discharge device is connected to ground through a path comprising condenser 193 and resistances 194 and 195, the point between resistances 15 194 and 195 being connected to the grid of discharge device 196. The anodes of these two discharge devices 192 and 196 are connected together through resistances 197 and 198, the point between these resistances being connected to ground through the source of anode potential 199. The positive terminal of this source is also connected through resistance 200 to the screen grids of the two discharge devices. Proper bias for operation of the two discharge devices 192 and 196 is obtained from the cathode bias resistor 201.

20 25 It will be seen that the electromotive forces, which appear on conductor 151, are amplified by device 192 and supplied in inverse phase to the grid of device 196. Thus the anode circuits of the two devices 192 and 196 operate in balanced relation to produce a voltage as indicated at M' on the anode of device 192 and as indicated at M'' on the anode of device 196. These voltages are supplied by means of conductors 203 between the vertical deflection plates of the train indicator.

30 35 Fig. 5 represents certain curves somewhat more clearly portraying the operation of the apparatus of Fig. 4. In this figure the signal supplied through condenser 166 is indicated by the wave 205. The aperture pulse, as supplied to the grid of the tube 161, is indicated by the wave 206. The aperture pulse, as it appears on the 40 anode of discharge device 161, is indicated at 207. The signal plus the aperture pulse as it appears upon the anode of a device 160 is indicated at 208 whereas the voltage which appears on the grid of device 162 is indicated at 209. The voltage on the anode of device 45 162 is indicated at M. This latter voltage is supplied over the long conductor 151 to the amplifiers 192 and 196 the anodes of which operate in balanced relation.

50 55 By reason of the form of the wave M the efficiency of operation of the devices 192 and 196 is materially improved; that is, the voltage of the wave M varies about equally in each direction from the steady state value. This means that the discharge devices 192 and 196 may be biased at a point about midway of their anode current grid voltage characteristics and the full range of this characteristic between saturation and cut-off may be utilized in amplifying the wave M.

60 The discharge devices 192 and 196 and the circuits therefor, may correspond to the equipment 132 of Fig. 2. A second pair of such discharge devices, similarly connected, may be employed to correspond with equipment 152 of Fig. 2. Of course, apparatus 130 of Fig. 1 includes circuits similar to those explained in connection with device 162 of Fig. 4 for supplying the desired voltage wave M to the equipment 152 of Fig. 2. The discharge devices 160 and 161 of Fig. 4 are included in the equipment represented by the rectangle 31 of Fig. 1.

70 75 The equipment of Fig. 4 possesses the advantage that the echo is reproduced at the output circuit as a variation from a voltage which is unaffected by variation in other signals or noise which may be received by the receiver at times other than during the aperture periods. This is by reason of the action of the grid condenser 166 and grid resistance 166' and by reason of the further fact that the pulses 15" corresponding to the trans-

mitted pulses are of constant amplitude having been limited to a constant amplitude by the receiver.

This action may better be understood by reference to Figs. 11a and 11b, which represent respectively two extreme conditions of the received signal. In Fig. 11a the curve 350 represents the voltage supplied from the receiver when only the pulses 15" and a single small echo 351 are received. The pulses 15" are of constant amplitude since they are limited in the receiver and the tops of these pulses correspond to substantially zero voltage on the grid of device 160. This is because the grid is prevented from going more than minutely positive by grid rectification. The alternating current axis of wave 350 is indicated at 352, this being a line which divides the areas between it and the wave 350 equally. Thus the distance x between this line 352 and the zero grid potential line 353 is the bias between the grid and cathode. The peak-to-peak amplitude of the pulses 15", being constant and determined by the receiver, is of such value that the grid is always at a voltage positive with respect to the value 354 which produces plate current cut off in the device 160 when the screen grid is positive during the aperture pulse. The most negative part of wave 350, corresponding to zero received carrier wave at the input to the receiver, never approaches the cut-off value 354 by less than the quantity Z .

In Fig. 11b the curve 350' corresponds to curve 350 of Fig. 11a, but is drawn to represent the situation when many large echoes are received at times other than when the relatively small desired echo 351 is received, the echo 351 being of the same intensity in both cases. The alternating current axis 352 is now nearer the zero grid voltage axis 353, the quantity X now being smaller than before. Since, however, the quantity y is the same as before, the quantity z is likewise the same as before. Therefore the plate current variation produced by echo 351 is about the same value of plate current as before being totally unaffected by the changed average value of the wave 350' from that of wave 350.

In other words, the effect of the pulses 15" of constant peak-to-peak amplitude is to tie the base of the echo 351 to a fixed position on the static characteristics of discharge device 160. Since rectification occurs at the positive peak of pulses 15" the negative peaks occur at a fixed point on the anode current grid voltage characteristic and the echo 351 is a variation from that fixed value. This value thus remains unchanged irrespective of what happens between echo 351 and the pulses 15".

The circuit of Fig. 4 is disclosed and claimed in a pending application of F. M. Deerhake, Serial No. 445,309, filed June 1, 1942, entitled Pulse Systems, now U.S. Patent No. 2,416,088, and which is assigned to the same assignee as my present invention.

In Figs. 3, 4 and 5 I have represented the aperture pulses of the wave M as modulated by a single echo. Of course more than one echo may be received during the aperture pulse.

Fig. 6 represents a further circuit which may be employed to accomplish the purpose of Fig. 4. In this circuit the signal is applied through condenser 215 to the grid of electron discharge device 216 in the positive sense. This device is normally biased to be conducting and its anode potential thus reduces in response to the signal. Thus, the signal is reproduced upon the anode of this device in the form indicated at 217. This signal is supplied in negative sense to the grid of amplifier 218 and is thus reproduced in positive sense upon the anode of this device as indicated at 219. The anode of this device, however, is connected in parallel with a second discharge device 220 to the grid of which the aperture pulse is applied in negative sense. Thus the aperture pulse is also reproduced in the wave 219 upon the anode of these devices and appears as indicated at 221 in the wave 219, the signal which occurs during the aperture pulse produces the modulation 222 at the top of the aperture pulse 221.

This wave 219 is now impressed upon the grid of discharge device 223 the anode of which is also connected in parallel with a discharge device 224 to the grid of which the aperture pulse is also applied in negative sense through condenser 225. The device 223 is so biased that it becomes conducting only during the period of the aperture pulse, that is, during the portion of the wave 219 above the dotted line 227. Thus, the anode potential of this device drops in accordance with that portion of the wave 219 above line 227. However, because of the action of device 224 this anode potential tends to rise during the aperture pulse, the resultant effect is that indicated at 230.

This may be better seen from Fig. 7 in which the wave 231 represents the signal applied to the grid of the device 218; the curve 232 represents the aperture pulse applied to the grids of devices 220 and 224; and the wave 233 represents the voltage which appears on the anodes of devices 218 and 220. The portion of this wave 233 above the dotted line 227 produces anode current in device 223 and thus tends to produce a voltage of the form indicated at 234. This voltage, however, when combined with the aperture pulse which appears at the anode of device 224 in the form indicated at 235, results in a wave of the form indicated at 236 in which the voltage variation may be equal at either side of the steady state value.

Fig. 8 shows the equipment represented at 65 in Fig. 2. This figure includes switch 20, of Fig. 2, which, when in its upper position, makes contact with conductor 64 to which the wave C is applied, and when in its lower position engages contact 87 to which the wave -D is applied. This switch 20 is connected to the grid of an electron discharge device 240, which includes in its anode circuit the two switches 21, shown within rectangle 65 of Fig. 2. This switch includes two movable contacts 241 and 242, each having two cooperating stationary contacts. These switches 242, 241 and 20 are all connected together mechanically by a member represented by the dotted line 243 to be moved simultaneously to their upper positions and to their lower positions. If we assume that the switches are in their upper position so that the wave C is applied to the grid of the discharge device, the anode circuit of the discharge device then extends as follows: From the positive terminal of the source of operating potential 244 through resistance 245 anode and cathode of discharge device 240, switch 241 in its upper position, load resistance 246, back to ground and the negative terminal of the source of operating potential. This device 240 is normally so biased that little or no current flows in its anode circuit except during the positive pulses of the wave C. This current flowing through the load resistance 246 reproduces the wave C upon this load resistance, the wave thus being supplied to the network 67, 68 of Fig. 2. This is the operation required to produce the 100 mile indication of device 12, which is indicated within the circle 13 of Fig. 2.

If switches 241 and 242 be in the lower position, then the anode circuit of the discharge device extends from the positive terminal of the source 244 through resistance 245, anode and cathode of device 240 and switch 242 in its lower position and resistance 247, back to ground and to the negative terminal of the source. Wave -D is now applied to the grid of the discharge device and produces current pulses in the resistance 245 in accordance with the wave -D. These current pulses result in a drop in voltage with respect to ground at the anode of the discharge device. This drop in voltage is supplied through condenser 248 and switch 241 in its lower position, to resistance 246 where it is reproduced in a negative sense with respect to the wave applied to the grid of the device 240. In other words, device 240 reverses the polarity of the wave -D to produce on resistance 246 the wave +D. This is the condition necessary to produce the 25 mile indication of device 12 as indicated within circle 13' of Fig. 2.

Fig. 9 represents the high frequency and low frequency

phase shifters 40 and 44 of Fig. 2, the high frequency phase shifter being indicated in the upper portion of the figure and the low frequency phase shifter being indicated in the lower portion of the figure. The mechanical connection between the two is indicated at 89.

Referring first to the high frequency phase shifter, the sine wave of voltage from the 82 kilocycle oscillator 56 is supplied to two buffer amplifiers 250 and 251. This wave is supplied to the amplifier 250 directly but it is supplied to the amplifier 251 through a phase shift network 252 whereby it is shifted in phase by ninety degrees. The outputs from these amplifiers 250 and 251, which are in quadrature phase relation, are supplied to respective coils 253 and 254, which may be the stator coils of a goniometer, for example. The coils 253 and 254 are positioned at right angles with respect to each other and thus produce a rotating field at 82 kilocycles within them. The coil 255 is mounted for manual rotation within coils 253 and 254 to have voltage induced therein of any desired time phase relation according to the position to which it is adjusted.

This coil is provided with slip rings 256 and brushes which are included in a circuit 257 which connects the phase shifter to the input of an amplifier and limiter 258. This amplifier and limiter 258 may be of any suitable type to produce square wave pulses at its output circuit. If we refer to Fig. 10-e in which the sine wave applied to the amplifier and limiter is represented at 259, the square wave output may be that represented in Fig. 10-e at 260. This square wave voltage is supplied to the grid of an amplifier 261, the anode circuit of which includes an inductance 262, a resistance 263 and a source of anode potential represented by the symbol B+, the negative terminal of this source being grounded at 264. The square wave applied to this grid produces square wave pulses of current through the load impedance comprising inductance 262, resistance 263, condenser 272, resistance 273, and stray capacity 266, these pulses of current being represented by the square wave 265 in Fig. 12. The stray capacity 266 exists inherently in shunt with the path comprising inductance 262, resistance 263, and by-pass condenser 271 and is indicated by the dotted lines 266. The result is that each change in current in inductance 262 is followed by an oscillatory transient in the circuit 262, 263, 271, 266. This oscillatory transient has a frequency determined by the constants of this circuit and it is much higher than the 82 kilocycle square wave. This transient is indicated at 270 in Fig. 12 where its first cycle 275 is indicated as of high amplitude and its later cycles being of rapidly diminishing amplitude throughout the period of each square wave pulse.

This square wave 265 and its oscillatory transient 270 are supplied to the path comprising condenser 272 and resistance 273. This path may include a source of negative bias potential 278 for the discharge device 280 and may terminate in ground. By reason of the operation of this condenser 272, the voltage of the square wave 265 is not reproduced as a square wave on the resistance 273 but rather appears thereon in the form of the wave represented by the dotted lines 274 in Fig. 13. That is, when the current is minimum in device 261 its anode is at high positive potential and the condenser 272 assumes a certain charge. During a positive pulse on the grid of this device 261, current increases in the anode causing condenser 272 to discharge to a certain extent through resistance 273. This current produces a voltage on resistance 273 represented by the portion *b* of the curve 274 of Fig. 13. During the negative portion of the square wave, the current drops in device 261 and its anode potential rises. Condenser 272 then commences to charge and current flows in resistance 273 in accordance with the portion *a* of the wave 274 of Fig. 13, and thus the cycle repeats. It will be seen that the portions *a* and *b* of the wave 274 are very steep and that the transient oscillation

previously mentioned is superposed upon this steep wave. However, because of the steepness of the portion *a* of the wave 274, the first positive swing 275 of the transient cycle extends to a much higher voltage than does the second positive swing 276, the difference in the peak values of these two positive swings being substantially greater than is the case in Fig. 12. This voltage is then supplied to the grid of the device 280 which is biased to be non-conducting for any voltages applied to the grid of value less than the positive value represented at *c* in Fig. 13. Thus, in the anode circuit of the device 280, only pulses of current such as those indicated at 275 appear. These pulses are represented in Fig. 10-f as occurring just after the zero points of the 82 kilocycle wave 259 represented in Fig. 10-e. These pulses 275 are the target marker pulses *F* of Figs. 2 and 3 and of course, they are shifted in their time phase relation with respect to waves from the oscillator 56 by variation of the position of the rotor coil 255 within the coils 253 and 254.

20 The low frequency phase shifter and aperture generator are shown in the lower portion of Fig. 9 and comprise electron discharge devices 279, 281, 282, 283 and 284. The discharge device 279 is supplied with operating potential from a source 285 which is shunted by a bleeder resistance 289, a variable tap on which is connected to the anode through an inductance coil 290. The cathode of the discharge device is connected to the negative terminal of the source 285 through a bias resistor 291. Screen grid potential is supplied to the screen grid of the discharge device from the positive terminal of the source 285 through a resistor 292, this screen grid being connected to ground through the usual condenser 293.

The wave *D* is applied between the grid and the cathode of the discharge device 279 and drives the grid thereof 35 of negative during the negative pulses of the wave. One negative pulse of the wave *D* is shown in Fig. 10-a. It will be remembered that the duration thereof corresponds to a time interval required for the wave to travel to an object 25 miles away and return. These negative pulses interrupt the anode current of the device 279 and thus cause condenser 294 to charge during the period of the negative pulse. This charge takes place in accordance with the left hand portion of line 300 of Fig. 10-b. Thus the potential at the point 301 increases with respect to ground in accordance with the left portion of the curve 300 of Fig. 10-b.

Across condenser 294 is connected a circuit comprising resistance 302 shunted by condenser 287, diode 281, and a resistance 303 the latter of which is connected to a tap 320 on a potentiometer 304 across the source of operating potential 285. Thus the cathode of the diode 281 is biased positively with respect to ground to a value greater than the positive potential at 301 by a variable amount indicated at 305 in Fig. 10-b, for example the amount of this bias may be varied by varying the movable contact on potentiometer 304. Thus during the first portion of the rise in voltage at point 301 corresponding to the dotted portion of the curve 300, no current flows in the diode. If a voltage corresponding to the horizontal line 306 of Fig. 10-b be exceeded, however, current flows in the diode and through resistance 303 to the potentiometer 304 and thus the potential of the cathode of the diode 281 becomes more positive in accordance with the portion of the curve 300 above line 306. This increase in positive potential of the cathode continues until the termination of the negative *D* pulse, when discharge device 279 again becomes conducting. The condenser 294 then discharges in accordance with the right hand portion of the curve 300 of Fig. 10-b. Thus the potential on the cathode of discharge device 281 is constant except during the latter portion of the charging period of condenser 294 when it increases and decreases in accordance with that portion of the curve 300 which is above the horizontal line 306.

The cathode of diode 281 is connected through a small condenser 310, which may be 100 micro-microfarads, for example, to the control electrode 286 of discharge device 282 and through resistance 311 to ground. So long as the potential on the cathode of the diode 281 is constant no current flows through the condenser 310 but during the rising period of the voltage on the cathode of diode 281, current flows through condenser 310 and resistance 311 as indicated by the portion 312 of the curve 313 of Fig. 10-c. This positive voltage on the control electrode of discharge device 282 increases the anode current therein causing a negative voltage to be applied to the control grid of discharge device 284 through condenser 288. This in turn decreases the anode current in the device 284 and the plate potential of that device rises driving the control electrode of device 283 in the positive direction. This causes device 283 to become conductive. This device is normally non-conducting because of the flow of anode current of device 284 through the resistance 315 which is included in the anode and grid circuit of device 283.

Anode potential on device 283 then drops forcing the control electrode of device 284 still further negative, additionally decreasing the anode current in that device. This action is cumulative and causes an extremely rapid rise in anode potential of device 284. This is the beginning of the aperture pulse.

During the period of the aperture pulse, condenser 288 discharges through resistance 316 until device 284 again becomes conducting by reason of reduced negative potential on its control electrode. Anode current in device 284 causes a drop in potential on the anode of device 283, which is now conducting, in the negative direction, reducing its anode current. Reduction in the anode current of device 283 drives the control electrode of device 284 additionally positive increasing its anode current, this action being cumulative and producing an extremely rapid termination of the aperture pulse which appears on the anode of device 284. This condition then exists until diode 281 again becomes conducting when a subsequent pulse such as that indicated at 312 of Fig. 10-c is applied to the grid of device 282. These pulses are supplied through condenser 317 and a buffer and limiter 318 to the aperture pulse bus 80 of Figs. 1, 7 and 9.

This aperture pulse is indicated in Fig. 10-d and is of a duration determined by condenser 288 and resistance 316. Preferably it has a duration corresponding approximately to the time required for a wave to travel from the equipment to a reflecting surface one half mile away and return, or 6 microseconds, or approximately one cycle of the 82 kilocycle wave.

This aperture occurs just at the beginning of the flow of current in diode 281, which is controlled in time by the adjustment of the variable contact on potentiometer 304. Thus, by adjustment of the potentiometer the aperture pulse, of constant duration, may be made to occur at any desired time during the twenty-five mile interval of pulse D.

The variable contact 320 of potentiometer 304 is mounted on a shaft which is geared to the shaft of the rotating coil 255 of the high frequency phase shifter for movement simultaneously therewith, so as to vary the time of occurrence of the aperture pulse in the twenty-five mile interval of the pulse D.

The 82 kilocycle wave has a frequency so chosen that one cycle is of a duration required for a wave to travel approximately one mile and back. Therefore, rotation of the coil 255 through 25 revolutions varies the phase of the wave 259 through the interval corresponding to the distance of 25 miles. The rotation of the gearing 321 between rotating contact 320 and rotating coil 255 is such that the contact 320 moves through its range of movement while the coil 255 rotates through twenty-five revolu-

tions. In this way the aperture pulse E of Fig. 10-d and the wave 259 of Fig. 10-e move simultaneously and synchronously and the pulse F of Fig. 10-f remains in fixed position with respect to the pulse E. Therefore, the inverted V-shaped deflection 35 seen on the range indicator remains in substantially fixed position thereon. Rotation of the shaft 89 varies the time of occurrence in the pulse D of both the aperture and the target marker pulse which produce the indication on the range indicator. The bright spot produced thereon by the received echo, as previously described, therefore, moves across the screen of the range indicator as shaft 89 is rotated and may be made to be equally divided by the vertex of the inverted V, thereby to provide an accurate measure of the distance to the reflector surface by which it is produced. This distance may be read from the scale 88 of Figs. 2 and 9.

As previously explained with reference to curves A, B, C and D of Fig. 3, the transmitted pulse, of curve B, occurs just after termination of pulse A. Pulse C terminates before termination of pulse A and hence before the transmitted pulses. Similarly pulse D begins before the transmitted pulses. These pulses C and D determine the periods of occurrence of the sweep periods of the control operator's indicator and therefore the transmitted pulse is indicated on the screen of that indicator at all times as is also the aperture pulse. By rotation of shaft 89 the aperture deflection 36, or 36', on Fig. 2 may be moved to a position where it includes or brackets the deflection produced by the transmitted pulses. This transmitted pulse, itself, then produces the bright spot on the range indicator and this bright spot may be adjusted in position with respect to the vertex of the inverted V-shaped deflection produced by the marker pulses. The position of shaft 89 which brings about this desired adjustment, which may be empirically predetermined, corresponds to zero distance. Any other angular position of this shaft with respect to this zero position, which other position produces a corresponding indication on the range indicator, corresponds to the distance to the reflecting surface producing the bright spot making up the indication. Thus, the rotation of the shaft may be linearly calibrated in terms of distance, by any suitable mechanism. The dial 88 in Figs. 2 and 9, is intended to represent any desired mechanism for effecting such calibration.

The adjustment of shaft 89 to a position where the radiated pulse is indicated by the bright spot on the range indicator bisected by the inverted V-shaped deflection produced by the target marker pulses F relates the radiated pulses to the fixed time in the cycle, or period, of the 82 kilocycle wave at which the target marker pulses occur. As previously mentioned these target marker pulses occur just after the zero points of the 82 kilocycle wave 259 represented in Fig. 10-e. Since the target marker pulses and radiated pulses are indicated at the same position on the range indicator they occur simultaneously. The position of the index on scale 88 then corresponds to zero range. Of course, this ignores the time delay in transmission of pulses in both ways between the duplexing device 98 and the antennae.

If shaft 89 be now rotated to delay the phase of the 82 kilocycle wave as induced in coil 255 and hence to delay the target marker pulses, the bright spot on the range indicator moves to the left until the delay amounts to 90 degrees of the 82 kilocycle wave, or three microseconds, or a time corresponding to one quarter of a mile of range, when it moves off the screen to the left. The delay may be increased by further rotation of shaft 89 each rotation corresponding to a delay of 12 microseconds, or one cycle, or period, or 360 degrees of the 82 kilocycle wave, which corresponds to one mile of range; and this delay may be increased, as previously mentioned, through twenty-five revolutions of the shaft 89, the index always corresponding in position on scale 88 to the range from which any echo is received, which echo is indicated on the range

indicator in position bisected by the inverted V-shaped deflection.

When the delay has been increased to an extent such that an echo is received within the aperture pulse, such echo is indicated by the bright spot coming on the viewing screen from the right and moving to the left with increase in the delay until it is bisected by the inverted V when the echo pulse is coincident in time with the target marker pulse and the range is indicated by the position of the index on the scale 88.

Thus, the mechanism relates both the radiated pulse and its echo to fixed respective positions in time on the 82 kilocycle wave, said positions being spaced apart by a number of periods of the wave corresponding to the number of revolutions of the phase shifter and by a time interval indicated by the position of the index on scale 88. Thus, the distance from which the echo is received is determined from the number of periods of the 82 kilocycle wave between the radiated pulse and its received echo.

The 82 kilocycle wave is, thus, the yardstick by which the time interval between the transmitted pulse and its echo is measured. The zero point of the yardstick is placed at the transmitted pulse by adjusting the target marker pulse to coincide in time with the transmitted pulse. This is done in the initial adjustment of the equipment. The target marker pulse is then moved along the yardstick in time through a number of periods of the 82 kilocycle wave, or a number of rotations of the phase shifter, corresponding to the unit space markings on the yardstick, until the target marker pulses agree in time with the desired echoes of the transmitted pulses. The position of the index on scale 88 then agrees with the number of periods of the 82 kilocycle wave, or the number of unit space markings on the yardstick, which are traversed and indicates the time interval, or distance, to be determined.

The system as thus described offers very great advantages with respect to the observation of moving objects which cannot be seen and with respect to following the movements thereof. One of its advantages results from the four cathode ray indicators, which, in effect, serve to divide the functions which must be performed by different operators to follow such a moving remote object. The control operators indicator, for example, may be positioned within easy vision of the operator who is in charge of the entire equipment. It enables him to select the remote object to be followed, and by adjustment of the aperture pulse, by control member 89, to confine the operation of the other indicators to that remote object. At the same time the square-shouldered deflection on the control operator's indicator aids the control operator himself in confining his attention to the echo indication produced by the desired remote object.

The range indicator may be positioned within easy vision of a second operator whose function it is to control shaft 89, thereby to maintain the inverted V-shaped deflection in position to bisect the bright spot on the screen. This controls the indication of distance to the remote object which may be made both locally and at a remote point as desired.

A third and a fourth operator may then be stationed to observe the train and elevation indicators respectively. These operators may also be provided with controls whereby they position the antenna array in train and in elevation respectively to maintain the two deflections on the respective indicators of equal height. This maintains the array directed at the remote object to be observed.

Thus, the functions performed by each of these operators is relatively simple, the operation being such that each operator may give his undivided attention to such individual relatively simple function. In this way the following of the remote object may be effected with the increased reliability with which the individual operators perform their individual simple functions as compared

with that which may be had if a single operator were required to observe the different instruments and operate all of the necessary controls.

While I have shown a particular embodiment of my invention, it will, of course, be understood that I do not wish to be limited thereto since various modifications both in the circuit arrangement and in the instrumentalities employed may be made, and I contemplate by the appended claims to cover any such modification as falls within the true spirit and scope of my invention.

What I claim as new and desire to secure by Letters Patent of the United States, is:

1. The combination, in a radio echo apparatus, of means to transmit a radio pulse and to receive echoes thereof, a cathode ray device having a viewing screen, means to supply to said cathode ray device two pulses, one shorter than the other and both shorter than the interval over which echoes are received, means to deflect the beam of said device across a predetermined path on said screen during the longer of said pulses and to deflect it from said path during the shorter of said pulses, and means responsive to a received echo during said longer pulse to vary the intensity of said beam thereby to vary the intensity of illumination of said path at the point corresponding to the time of reception of said echo.
2. The combination, in a radio echo apparatus, of means to transmit a radio pulse and to receive echoes thereof, a cathode ray device having a viewing screen, means to supply to said cathode ray device two pulses, one shorter than the other and both shorter than the interval over which echoes are received, means to deflect the beam of said device across a predetermined path on said screen during the longer of said pulses and to deflect it from said path during the shorter of said pulses, means responsive to a received echo during said longer pulse to vary the intensity of said beam thereby to vary the intensity of illumination of said path at the point corresponding to the time of reception of said echo, and means to vary the time of occurrence of said shorter pulse to produce coincidence between said point and the deflection from said predetermined path produced by the shorter pulse.

3. In an echo apparatus, means to produce periodic pulse waves, the pulses of one polarity of which have a duration corresponding to the time over which echoes are received, means to produce a further periodic pulse of the same frequency and short relative to said pulses of one polarity, a movable element, means to adjust the time in said pulse of one polarity when said short pulse occurs by movement of said movable element, means to produce a high frequency rotating field, pick up means rotatable in said field, said pick-up means being mechanically geared to said movable member with such ratio that the electromotive force picked up thereby is variable in time phase synchronously with said short pulse, means to produce from said electromotive force a further pulse occurring during said short pulse, indicating means responsive to echoes received during said short pulse, and means responsive to said further pulse to control said indicating means.

4. The combination, in a pulse reception system in which periodically recurring trains of pulses are received, each of said trains comprising an intense pulse followed by a succession of pulses of varying intensity, of a discharge device having an anode circuit, a cathode, and a control electrode, means to limit said intense pulses to pulses of constant amplitude at least as great as the most intense of said following pulses and to supply said trains of pulses between said grid and cathode, means to produce peak rectification of said intense pulses between said grid and cathode thereby to provide a fixed bias from which the individual pulses of said trains vary, and means to render said discharge device conducting only during the period of a selected portion of said pulses whereby said selected portion of said pulses is reproduced in said

anode circuit as a variation from a value of current in said anode circuit constant irrespective of the intensity of other pulses of said trains.

5. In combination, an electron discharge device having an anode, a cathode, and a control electrode, an anode to cathode operating circuit for said device, means to supply between said control electrode and cathode trains of pulses, each train comprising a strong pulse of constant amplitude and other weaker pulses of varying amplitude, means to produce peak rectification of said strong pulses thereby to produce a constant bias voltage between the grid and cathode, said bias voltage being of a value less than the value which cuts off the current flowing from the anode to the cathode of said tube whereby each pulse is reproduced in said operating circuit as a variation from a value of anode current which is fixed irrespective of the intensity of other pulses in said trains, and means to render said discharge device normally nonconductive and to render it conductive during a desired portion of any train of pulses.

6. The combination, in an echo apparatus, of means to transmit periodic pulses and to receive echoes thereof, a cathode ray device having a viewing screen, means to deflect said ray across said screen in either of two different desired time intervals and to control said ray during said intervals in accord with the echoes received, said means comprising means to generate a square wave, means to integrate said wave, means to deflect said ray in accord with the wave resulting from said integration, and means to control said square wave to produce said deflection in either of said two desired intervals.

7. The combination, in an echo apparatus, of a cathode ray device having a viewing screen, means to deflect said ray across said screen in either of two different desired time intervals corresponding to different ranges from which echoes are received, said means comprising means to generate either of two square waves in accord with the time interval of deflection desired, one of said waves comprising periodic positive pulses and the other periodic negative pulses, said pulses being short relative to the period between said pulses and occurring substantially end to end in time, means to integrate said pulses, and means to control said deflection in accord with the wave produced by said integration.

8. The combination, in an echo apparatus, of a cathode ray device having a viewing screen, means to deflect said ray across said screen in either of two different desired time intervals corresponding to different ranges from which echoes are received, said means comprising means to generate either of two square waves in accord with the range desired, one of said waves comprising periodic positive pulses and the other periodic negative pulses, said pulses being short relative to the period of the pulses and occurring substantially end to end in time, a resistance and a condenser, means to supply either one of said waves or the other, as desired, through said resistance to said condenser, and means to control the deflection of said ray in accord with the potential on said condenser.

9. The combination, in an echo apparatus, of a cathode ray device having a viewing screen, means to deflect said ray across said screen in either of two different desired time intervals corresponding to different ranges from which echoes are received, said means comprising means to generate either of two square waves in accord with the time interval of deflection desired, one of said waves comprising periodic positive pulses and the other periodic negative pulses, said pulses being short relative to the period of the pulses and occurring substantially end to end in time, a resistance and a condenser, means to supply either one of said waves or the other, as desired, through said resistance to said condenser, means to control the deflection of said ray in accord with the potential on said condenser, and means responsive to said square

wave supplied to said resistance to interrupt said ray during the retrace periods thereof.

10. The combination, in an echo apparatus, of means to radiate periodic pulses and to receive echoes thereof, said means comprising a directive antenna, means to alternate the directive pattern of said antenna between two positions at a predetermined frequency, a cathode ray device having a viewing screen, means to deflect the ray across said screen during a short portion of the period between said periodic pulses, means to control said ray in accord with an echo received during said short period, and means to vary the center about which said deflection occurs in the direction in which said deflection occurs between two points on said screen in the trace over which said ray is deflected synchronously with said alternation whereby echoes received during said short portion of said period produce two indications side by side on said screen along said trace over which said ray is deflected by said deflection means one being produced by echoes received when said pattern is in one position and the other being produced by echoes received when said pattern is in its alternate position.

11. The combination, in an echo apparatus, of means to radiate periodic pulses and to receive echoes thereof, said means comprising a directive antenna, means to rotate the directive pattern of said antenna through four positions in succession two in train, and two in elevation, a pair of cathode ray devices having viewing screens, means to indicate on one of said screens pulses received when said pattern is in said positions in train, and to indicate on the other of said screens pulses received when said pattern is in said positions in elevation, said indications on said screens being in positions thereon corresponding to the respective position of said pattern, and means to vary said indications in accord with the intensity of the received pulses from which they are produced.

12. The combination, in an echo apparatus, of means to radiate periodic pulses and to receive echoes thereof, said means comprising a directive antenna, means to rotate the directive pattern of said antenna through four positions about the surface of a cone in successive order, a pair of cathode ray devices, each having a viewing screen, means to operate said cathode ray devices alternately to indicate on their respective screens echoes received when said pattern is in respective pairs of said four positions, said echoes received when said pattern is in opposite positions of each pair being indicated in corresponding positions on the respective screen, and means to vary each indication in accordance with the intensity of the echo received when said pattern is in the respective position.

13. The combination, in an echo apparatus, of means to radiate periodic pulses and to receive echoes thereof over a predetermined interval, said means comprising a directive antenna, a pair of cathode ray direction indicators, each having a viewing screen, means to supply echoes received during a small portion of said interval to each of said indicators to produce a visible indication on the screen thereof, means to rotate the directive axis of said antenna through four positions about the surface of a cone, echoes received when said axis is in one pair of opposite positions being supplied to one of said indicators and those received when said axis is in the alternate pair of opposite positions being supplied to the other indicator, and means to produce said indications of said echoes on each viewing screen in two positions each corresponding to a respective one of the corresponding pair of positions of said axis.

14. The combination, in pulse echo apparatus, of means to transmit periodic radio pulses and to receive echoes thereof between the transmitted pulses, two cathode ray devices, means to deflect the ray of one of said devices across its screen with a given sweep velocity during the time interval of reception of said echoes and to

produce variations on the screen at points corresponding to the times when echoes are received, means to supply to the other of said devices two periodic pulses, one shorter than the other and occurring during the other and both being short relative to said time interval, means 5 to deflect the beam of said other device across its screen during the longer of said two pulses with a sweep velocity greater than said given velocity and to produce variations therein recognizable on the screen at points corresponding to the times of occurrence of received echoes and of 10 occurrence of said shorter pulse, means to supply the longer of said pulses to said one device to produce a recognizable variation on the screen thereof at a point corresponding to the time of occurrence of said longer pulse, and means to vary the phase of said two pulses 15 in time to produce coincidence of said two recognizable variations on said other screen.
